AURIN WOOD, OF WORCESTER, MASSACHUSETTS.

Letters Patent No. 79,714, dated July 7, 1868

IMPROVED MACHINE FOR THREADING BOLTS.

The Schedule referred to in these Letters Patent and making part of the same.

KNOW ALL MEN BY THESE PRESENTS:

That I, AURIN Wood, of the city and county of Worcester, and Commonwealth of Massachusetts, have invented certain new and useful Improvements in Bolt-Cutters; and I do hereby declare that the following is a full, clear, and exact description of the same, reference being had to the accompanying drawings, forming a part of this specification, in which—

Figure 1 represents a top or plan view.

Figure 2 represents a side view.

Figure 3 represents a longitudinal central section on line A B, fig. 1.

Figure 4 represents a cross-section on line C D, fig. 1; and

Figure 5 represents upon an enlarged scale one of the dies, and the cams for operating the same, as will be hereafter explained.

To enable those skilled in the art to which my invention belongs to make and use the same, I will proceed to describe it more in detail.

In the drawings, the bed is lettered A, upon the upper side of the rear end of which is fitted to turn in a suitable bearing or box, a, the main spindle B, having a hole, b, which extends through its entire length. Upon the middle of the spindle B is a screw-thread, e, upon which are screwed a flanged nut, C, and the check-nut C'. D is a cam-ring, which works loose upon the spindle B. It has a flange, d, to which is fastened the flange-ring e, the lip 1 of which fits over and back of the flange 2 of nut C.

There are two notches cut in the flanges d e, one on each side, for a purpose hereafter explained. The cam-ring D has a slot, 3, running entirely around it, said slot being cut so as to form, in this instance, four cams 4.

E is a ring, loose on the spindle B, having two sets of horizontal slots cut in its flange part, E', in one set of which are fastened the ends of two rear projecting arms i i, having pins 4, which fit into the slot or cam-groove 3 in cam-ring D, while in the other set are fastened the ends of the forward-projecting die-operating arms G. In this instance, four are used. The die-operating arms G work in grooves or slots cut in the head B'. The case F being fastened to and turning with the head B', protects and covers the arms G on their outer sides. H are the cutting-dies, fitted to work back and forth in slots cut in the face of the head B'. Each die has a straight groove, 7, and a lip, 8, to fit into and lock with the groove 9 and lip 10 of each locking-piece I, which latter have inclined grooves 11 and lips 12 to lock with the grooves 13 and lips 14, on the front ends of the die-operating arms G. When the parts are combined together they occupy the relative positions indicated in figs. 3 and 4 of sheet 2 of the drawings.

In fig. 5, same sheet, the arm G, die H, and the locking-piece I are shown upon an enlarged scale. The arm G and die H are represented in their relative positions, while the connecting-piece I is shown detached and turned around. It will be observed that the wedge part 15 of the part I fits in between the lips 8 and 14 of the parts H and G, so that as the arm G is moved back and forth, a reciprocating or back-and-forward motion will be imparted to the piece I and die H, at right angles to the line of motion of the arms G.

The head B' is slotted or cut out to receive and hold the dies H and connections I in their respective and proper positions as they are worked by the arms G, a face-plate, K, being fastened to the front of the head B' to prevent the dies and connection-pieces from working or dropping out in front. Holes 16 are cut in the face-plate to admit of the tapering ends 16 of the arms G to work through; also with a central hole, 17, through which the end of the blank bolt can be passed to the cutting-dies.

Between and upon the ways 18 18 of the front of the frame A the carriage L is fitted to slide. To the rear end of the carriage L is fastened a rack-bar, L', into the cogs or teeth m of which mesh the teeth n of the gear M upon the shaft M', which has its bearings in the sides of frame A, and having upon one end, which projects through the side of frame A, a friction-wheel, N, fastened.

Upon the top of the rack-bar L' is fastened a trough-piece, L'', which serves to hold the blank and the cut bolts.

In the front of the carriage L are fitted two vertical-sliding clamp-pieces O O, their ends working up and down in dove-tailed grooves in the sides of the carriage L.

A hand-wheel, O', is fastened to the top of a screw-spindle, O'', which passes down through the ends of both of the pieces O, the thread on said spindle being cut right-handed for moving one piece, O, and left-handed for moving the other piece, so that when said wheel is moved in one direction, the clamping-pieces O O will be moved from each other, while, when it is moved in the opposite direction, said pieces will be moved towards each other; said pieces being so set that when drawn close together, they will meet upon a plane on a line with the axis or centre of motion of the spindle B.

The screw-spindle O'' is held in place, so that it cannot move longitudinally, by the stand Q fastened to the top of one side of carriage L, and through which the spindle passes, a collar being fastened to spindle O'' under the stand. Through one side of the carriage L is inserted a rod, o, which can be adjusted back and forth, and then secured in place by the screw p.

A small journal or shaft, y, is inserted in the side of frame A, having attached to its inner end a dog, s, while to its outer end is fastened the arm t, the long end resting on the pin u, and the short end working up under the end, v, of lever P, which is pivoted at 20, and is also connected by the bent cross-connection P' to the sleeve P'', which, in turn, is hinged by the swivel-clasp 21 to frame A. Within the sleeve P'' is a loose rod or piston, 22, which is free to slide back and forth in said sleeve.

The rear end of the rod 22, when its sleeve P'' is turned in, as shown in fig. 1, will be passed by the cam 23 upon the inner face of wheel 24, but when it is thrown out, as it is when the short end of lever t is depressed so as to let spring w force lever P towards the spindle B or centre of the machine, cam 22 will strike it and force it back against a spring-piston in the case w', fastened to the side of carriage L.

An arm or finger-piece, x, extends in from lever P, which is forced into the notches y in the flanges d e, when lever P is forced in as above described. There are two notches y in the flanges d e, one on each side, one side of the notch being inclined and the other square.

Q' is a device for holding the blank bolts while the thread is being cut. It is made with a slot, wide enough to receive the head of the bolt, while the slot back of the head is extended sufficiently to admit of the fastening of the spring 25 to the piece Q', as indicated in fig. 3, for the purpose of pressing up against the head of the bolt to keep it in place while being run to the dies.

The front part of the piece Q' is slotted out to receive the body of the bolt, and support it in a central position. From the back of the piece Q' a finger, Q'', projects, and which finger is inserted and clasped between the jaws O O.

When long bolts are to be cut, the body of the bolt can be run through between the jaws O O, by which it can be held during the operation of cutting, the holder Q', in such cases, being dispensed with. Rod o is used for determining the length of thread to be cut upon the bolt.

As the dies wear, or when putting in new ones, and it becomes necessary to adjust them so as to admit a rod of any particular size, check-nut C' is turned back, and then nut C turned forward or back, as may be desired, until the dies H are moved to the proper position to cut the desired thread when check-nut C' is turned up. To determine how much the dies have been moved in either direction, after having been once adjusted, a slot, 31, is cut in the case F, just over one of the die-operating arms, G, and a screw, 32, passed through said slot, and screwed on to the arm G.

After the screw has been inserted, a cut is made in the head, to correspond with the cut 33 in the case F, the cut being made when the pins 4 are in the front parts of groove 3. Now, as arms G are moved forward or back by the movement of nut C, for the readjustment of the dies, the extent of such movement will be indicated by the extent of the disagreement between the marks or cuts above alluded to.

The dies may be made so as to dispense with the connections I, the die being made longer, and the inclined groove 11, shown in the connection I cut in the die to receive the tongue of arm G. I prefer, however, to use the connections for several reasons: First, the labor of making the inclined grooves is more difficult than making a simple straight groove; second, it would be quite difficult for many workmen to fit the parts so as to have them work easily, while the same workmen would have no trouble in making the die H with simply a straight groove, 7; third, as the dies wear out, it is much easier to make them, as shown in fig. 5, than it would be if the connections were not used.

In cutting long bolts, the trough L'' answers an excellent purpose for supporting the rear ends while the thread is being cut. It will thus be seen that trough L'' is a very useful and convenient device in cutting all kinds of bolts.

The operation is as follows:

The dies being run down to the lowest point, and power being applied to give motion to the spindle B in the direction indicated by arrows, figs. 1 and 2, and the carriage L being run back, the operator inserts a blank bolt in the holder Q', then takes hold of lever R, which turns loosely on shaft M', and, bearing it down, produces sufficient friction between the piece R', hinged to its short end, (see fig. 2,) and the rim of the wheel N, to move shaft M', thereby turning gear M, and which, acting upon rack L', moves carriage L, with the blank bolt, forward. After lever R has been depressed, so that it strikes on pin 26, the operator turns it back, or allows spring 27 to force it back for a new hold on wheel N; the hinged piece R' turning on pivot 28, whereby no friction on wheel N is produced by the backward motion of the lever, and wheel N stands still until the lever is forced down again.

By a repetition of such movements of lever R, the carriage L is fed forward until the end of the blank is caught between the dies H, when the cutting of the thread continues, and the end of the bolt is drawn in by the action of the dies until a sufficient length of thread has been cut upon the bolt, when the rod o strikes against

the dog or arm 5, and depresses the front end of lever *t* sufficiently to allow the front end of bar *P* to slip over it, whereby the finger *x* enters one of the notches, *y*, and stops the motion of the cam-piece *D*, while the head *B'*, continuing to revolve, carries around with it the die-operating arms *G*, ring *E*, and arms *i*, whereby, as the pins *4* are forced into the rear part *34* of groove *3*, ring *F*, together with the die-operating arms *G*, is drawn back, and the connection-pieces *I* and dies *H*, drawn out so that the threads of the dies are freed from the threads cut in the bolt, by which time cam *23* comes in contact with the end of rod *22*, driving it back suddenly against the spring-piston in the shell *w*, attached to carriage *L*, which sudden action throws the carriage back sufficiently to draw the end of the bolt clear from the dies *H*.

As the head *B'* continues to revolve, pins *4* are forced into the forward part of groove *3* again, thereby forcing ring *E* and arms *G* forward, and the connections *I* and dies *H* in again to the proper positions to cut the thread on another bolt, when the cam *29* on the case *F*, acting on the projection *30* on lever *P*, forces out the front end of the latter far enough to clear the finger *x* from the notch *y* in flanges *d* and *e*, and so that the short end of lever *t* can fly or rise up between the side of frame *A* and the front-end *v* of lever *P*, as indicated in fig. 1.

The die-cutting apparatus is now ready for another blank to be fed in, and will remain and revolve in this condition, including the cam *D*, until another is fed in, when the operation above described will be repeated.

It will be observed that after the operator has put in the blank and moved carriage *L* forward far enough to have the dies catch the end of the blank, no further attention is necessary until after the bolt is cut and carriage *L* run back, as above described. Further, that the dies are run out to clear the threads of the bolt, and then run back again after the bolt has been withdrawn to the proper positions to cut the thread on the next blank by mechanism, which operates automatically, so that one attendant can run two or three of my improved machines nearly or quite as easily as one of the bolt-cutters in common use.

Still, again, it will be noticed that the arrangement for feeding the carriage forward to enter the end of the blank between the dies is such that the operation does not require much labor, while there is no lateral straining or twisting of the carriage, which is apt to interfere with the proper and correct entering of the end of the blank between the dies. If preferred in any case, the bolts may be run in and the dies run over the thread a second time, as indicated in the drawings. As a general rule, the thread will be completed by the first operation.

Having described my improved bolt-cutter, what I claim therein as new and of my invention, and desire to secure by Letters Patent, is—

1. The arrangement, with the spindle *B*, head *B'*, and case *F*, of the cam-ring *D*, arms *G* *i*, locking-pieces *I*, and dies *H*, the parts being constructed and operating in connection with each other, substantially as and for the purposes set forth.

2. The notched stop or flanged collars *d* *e*, in combination with the cam-ring *D* and arms *i* and *G*, the said parts being constructed and arranged in the manner set forth, to open and close the threading-dies, substantially as described.

3. The combination of the rod *o* with weighted lever *t*, arm *s*, cam *29*, and lever *P*, provided with arms *x* and *30*, said parts being arranged for operation to stop and release the notched or flanged collars *d* *e*, substantially as and for the purposes described.

4. The cam *23* on the wheel *24*, and the rod *22* working in the sleeve *P''*, in combination with the spring-stop, said parts being arranged to throw back the blank-carriage after the threading dies are opened, substantially as described.

5. The rod *o*, weighted lever *t*, arm *s*, cam *29*, and lever *P*, with its arms *x* and *30*, in combination with the connection *P'*, sleeve *P''*, and notched or flanged collars *d* *e*, substantially in the manner and for the purposes set forth.

6. The combination of spring *27*, lever *R* *R'*, wheel *N*, with rack, pinion, and the blank-carriage, said parts being constructed and arranged substantially as and for the purposes set forth.
